UNITED STATES PATENT OFFICE.

FRED J. KEPPLER, OF BUFFALO, NEW YORK.

CONVERTIBLE BUILDING.

Application filed May 22, 1920. Serial No. 383,418.

To all whom it may concern:

Be it known that I, FRED J. KEPPLER, a citizen of the United States, residing at Buffalo, in the county of Erie and State of New York, have invented new and useful Improvements in Convertible Buildings, of which the following is a specification.

This invention relates to a convertible building of the general type shown in my co-pending application No. 302,569, filed June 7, 1919, and the object of the present invention is to provide improved means for removably mounting posts between the floor and ceiling of a building and also detachably connecting portable walls or partitions with said posts, so that the space within the building may be readily subdivided into compartments of various forms, sizes and numbers as occasion may require.

In the accompanying drawings: Figure 1 is a fragmentary sectional elevation of a building equipped with my improvements. Figure 2 is an enlarged sectional elevation, showing a coupling head connecting a post, and partitions with a ceiling in accordance with my invention. Figures 3, 4 and 5 are horizontal sections taken on the correspondingly numbered lines in Fig. 2. Figures 6 and 7 are vertical sections taken on line 6—6 and 7—7, respectively, in Fig. 2. Figures 8 and 9 are perspective views of parts of the devices whereby the partition is slidably connected with a post. Figure 10 is a fragmentary vertical section taken lengthwise of one of the arms of the supporting body and showing a modification of my invention. Figure 11 is a transverse section taken on line 11—11, Fig. 10.

Similar characters of reference indicate corresponding parts throughout the several views.

10, 11 represent the horizontal floor and ceiling of a building which may be constructed in any suitable manner so that the floor and ceiling are maintained in position relative to each other, so that the space between the same may be sub-divided as desired by means of my invention. The means whereby this space is sub-divided consists generally of a plurality of upright junction members, posts, columns or standards 12, couplings 13 interposed between the ends of each post and the ceiling and floor and partitions 14 engaging their upper and lower horizontal edges with the ceiling and floor and connected at their vertical edges with

the posts while the corners are connected with said couplings.

Each of the posts 12 has its body preferably constructed of wood which is square in cross section and has its upper and lower ends reduced and provided with metal caps 40. Between the upper and lower ends of the post are arranged couplings whereby the post is removably secured to the support formed by the ceiling and floor, and the partitions are also supported relatively to the posts, ceiling and floor. The couplings at opposite ends of each post are substantially alike and the following description of one will therefore apply to both.

Each of these couplings comprises a hollow body or frame having a horizontal plate 41 adapted to engage either the ceiling or the floor, a socket 15 on the central part of said body and a plurality of hollow radial arms 16, the latter being preferably four in number and arranged equidistant around said socket. The bodies of the couplings for the ceiling are preferably secured permanently to the latter by means of screws 17 but the bodies of the couplings for the floor preferably rest thereon by gravity and are also frictionally engaged therewith so that the same may be entirely removed when not required and thus leave the floor clear of obstruction and without any mutilation. The reduced cap at one end of each post is adapted to be alined with the socket of one of the coupling bodies and to be detachably connected therewith by a clamping device which in its preferred form consists of a follower 18 having an external screw thread engaging with an internal thread in the socket 15 and adapted to bear at its outer end against the adjacent end of the post for holding these parts in position relatively to each other. The turning of the follower for engaging or disengaging the same with the post is preferably effected by providing the outer end of the peripheral portion of the follower with an annular row of openings 19 which may be engaged one after another by a tool or pin which is passed through a slot 20 in the side of the socket and then moved one way or another for turning the follower in the desired direction for tightening or loosening the same on the post.

Each of the partitions, walls or panels 14 is provided at its corners with a recess 21 which in the assembled position of the parts receives an arm on one of the coupling

bodies so as to form a practically closed joint therewith and effect a complete separation of the compartments or rooms within the building on opposite sides of the partition. In order to hold the partition in its upright position, the same is interlocked with each of the coupling bodies by means which may be variously constructed but which in the form shown in the drawings 10 are constructed as follows:

22 represents a plurality of clamping levers one of which is pivoted to swing vertically within each arm of the coupling body by means of a pivot bolt 23 passing through 15 this lever and a pair of lugs 24 projecting from the inner side of the plate 14 of the coupling body. At its outer end the clamping lever is connected with the rear side of a retaining ball or spherical catch 25 which latter is arranged to move vertically in a 20 guide pocket 26 in the outer end of the respective arm of the coupling body and normally projects with its spherical front side beyond the front side of the body 25 arm. The retaining catch 25 is preferably pivotally connected with this lever by a bolt 27 passing through this lever and a pair of lugs 28 on the rear side of the catch, as shown in Figs. 2 and 6. Each of the clamping levers is turned yieldingly in the direction for moving the retaining catch beyond the front side of the coupling body by means which preferably comprise a guide pocket 29 arranged on the central part of the coupling body in line with the inner arm of the respective clamping lever, a follower 30 bearing against the inner side of this lever and guided in said pocket, and a spring 31 arranged in said pocket and engaging one end with the bottom thereof while its opposite end bears against said follower. In the horizontal edge portion of each of the recesses on the partition the same is provided with a seat 32 preferably 45 of spherical form which is adapted to receive the spherical face of one of the catches or retaining members, this seat being formed in a metal cap 33 secured to the upper edge of the partition by means of screws 34 or otherwise. On its opposite 50 lateral sides this cap is provided with two inclined trough-shaped guides 35 which lead up to opposite sides of the seat 32 and serve to direct the catch 25 into this seat when 55 assembling the parts.

In the operation of dividing the space between the ceiling and floor into compartments, a coupling body is first placed on the floor in line with each of the coupling bodies which is secured to the ceiling and between which and the respective floor coupling body a post is to be erected. A post 60 is now placed vertically in line with the sockets of a pair of ceiling and floor coupling bodies and then the followers 18 in

the sockets thereof are turned until they bear firmly against opposite ends of the post and hold the same securely in place. A partition is now placed in an upright position and moved laterally so that the trough guides 35 on one side thereof engage the catches of the respective coupling bodies and deflect the same until the partition spans the space between a pair of posts at which time the catches will engage the respective seats of the partition and hold the same in place. To prevent disengagement of the catches from these seats by a lateral pressure against the partition, means are provided for locking the catches in engagement with their seats which means preferably consist of locking pins 36 screwed into opposite sides of each catch and each passing through a slot 37 formed partly in the lower edge of the coupling body and partly in the upper side of the cap 33 in which the catch seat is formed. By this means a party occupying a room on one side of a partition cannot unfasten the partition and gain access to the room on the opposite side of the partition, thereby preventing intrusion and ensuring privacy and safety of the occupants of the respective rooms.

Obviously, one or more partitions may be associated with each post and the respective couplings depending upon the manner which it is desired to divide the space. Inasmuch as the couplings are all alike in construction and operation, the same are capable of universal use regardless of whether the same are applied to the ceiling or the floor and also regardless of whether only one or a plurality of partitions are associated with the same and the companion post.

Furthermore, this construction is very 105 simple and easily operable which renders it easy to either put up the partitions or take them down, as desired.

Moreover, this construction permits of readily opening up the entire space between 110 the ceiling and floor when the same is desired for dancing or other purposes and as quickly subdivided into separate rooms, thus rendering the same particularly suitable for camping or outdoor life.

The mechanism within each supporting body is preferably concealed from view by securing a cover 60 over the front or outer side of the body by means of screws 62, or otherwise, said cover being provided with 120 hand holes 61 through which the levers 22 may be grasped and operated in the event that the same become stuck.

In the modified construction of my invention shown in Figs. 10 and 11, each spherical catch 25 is mounted on the outer end of a lever 50 which is pivoted at its inner end by a pin 42 on a lug 43 formed on the adjacent part of the hub 15 of the supporting body and this catch is yieldingly 130

held in engagement with a socket 44 on the partition 14 by a spring 45 which in this case has the form of a leaf and is interposed between the upper side of the lever 50 and the base plate 41.

I claim as my invention:

1. A convertible building having a support, a coupling body mounted on said support, a partition, and means for detachably connecting said partition and support comprising a catch member and a seat member adapted to receive said catch member, one of said members being mounted on the coupling body and the other being mounted on the partition. 60
2. A convertible building having a support, a coupling body mounted on said support, a partition and means for detachably connecting said partition and support comprising a seat arranged on the partition, a lever pivoted on the coupling body, and having a catch adapted to engage said seat, and a spring for yieldingly holding said catch in its operative position. 65
3. A convertible building having a support, a coupling body mounted on said support, a partition and means for detachably connecting said partition and support comprising a seat arranged on the partition, a lever pivoted on the coupling body and having an outer arm and an inner arm, a catch arranged on the outer arm and adapted to engage said seat, and a spring operating on the inner arm for holding the lever in its operative position. 70
4. A convertible building having a support, a coupling body mounted on said support, a partition, and means for detachably connecting said partition and support comprising a seat arranged on the partition, a lever pivoted on the coupling body and having an outer arm and an inner arm, a catch arranged on the outer arm and adapted to engage said seat, a guide pocket arranged on the body in line with said inner arm, a follower arranged in said pocket and engaging said lever, and a spring arranged in said pocket between said follower and the bottom of said pocket. 75
5. A convertible building having a support, a coupling body mounted on said support, a partition and means for detachably connecting said partition and support comprising a spherical seat arranged on the partition, a spherical catch mounted on the body engaging with said seat, and a guide pocket on said body for said catch. 80
6. A convertible building having a support, a coupling body mounted on said support, a partition, and means for detachably connecting said partition and support comprising a catch member and a seat member adapted to receive said catch member, one of said members being mounted on the coupling body and the other being mounted on the partition, and a guide on said partition for said catch and leading to said seat. 85
7. A convertible building having a support, a coupling body mounted on said support, a partition and means for detachably connecting said partition and support comprising a spherical seat arranged on the partition, a spherical catch mounted on the body engaging with said seat, and two guides arranged on opposite sides of said partition and leading to said seat to direct said seat in position to be engaged by the catch. 90
8. A convertible building having a support, a coupling body mounted on said support, a partition and means for detachably connecting said partition and support, comprising a catch member and a seat member adapted to receive said catch member, one of said members being mounted on the coupling body and the other being mounted on the partition, and means for locking said catch in engagement with said seat. 95
9. A convertible building having a support, a coupling body mounted on said support, a partition and means for detachably connecting said partition and support comprising a spherical seat arranged on the partition, a spherical catch mounted on the body engaging with said seat, and locking pins detachably connected with said catch on opposite sides of said partition and adapted to engage with said body for retaining the catch in engagement with said seat. 100
10. A convertible building having a support, a coupling body mounted on said support, a partition and means for detachably connecting said partition and support comprising a spherical seat arranged on the partition, a spherical catch mounted on the body engaging with said seat, and locking pins detachably connected with said catch on opposite sides of said partition, said body and seat having their opposing parts constructed to form slots which receive said pins. 105

FRED J. KEPPLER.
